TRAY FOR A CAR SEAT REST

Frank B. Cohen, 156 Barbados, Tampa, Fla.

Filed July 10, 1964, Ser. No. 80,803

Term of patent 14 years

(Cl. D44—10)

FIG. 1.

FIG. 2.

FIG. 3.

I claim:

The ornamental design for a tray for a car seat rest, as shown.
